CLAIM

The ornamental design for a gaming machine, as shown and described.

DESCRIPTION

FIG. 1 is an oblique view of a gaming machine showing an embodiment of the design;

FIG. 2 is a front view thereof;

FIG. 3 is a rear view thereof;

FIG. 4 is a right view thereof;

FIG. 5 is a left view thereof;

FIG. 6 is a top view thereof; and

FIG. 7 is a bottom view thereof.

FIG. 8 is an oblique view of a gaming machine showing an alternate embodiment of the design;

FIG. 9 is a front view thereof;

FIG. 10 is a rear view thereof;

FIG. 11 is a right view thereof;

FIG. 12 is a left view thereof;

FIG. 13 is a top view thereof; and,

FIG. 14 is a bottom view thereof.

(Continued)

Dashed (broken) lines represent structure or features that form no part of the claimed design.
